(57) **CLAIM**

The ornamental design for a teardrop shaped tweezer device, as shown and described.

DESCRIPTION

FIG. 1 is a top plan view of the device;

FIG. 2 is a right side view of the device;

FIG. 3 is a left side view of the device;

FIG. 4 is a front view of the device;

FIG. 5 is a rear view of the device;

FIG. 6 is a cross-sectional view of the device along line 6—6 of FIG. 1; and,

FIG. 7 is a cross-sectional view of the device along line 7—7 of FIG. 1.

The portions shown in broken lines are for illustrative purposes only; and form no part of the claimed design.
